United States Patent Office

Des. 216,511

Patented Jan. 27, 1970

216,511

BULK MATERIAL CONTAINER

Clarence B. Coleman, Oakland, Calif., assignor to
Fabricated Metals, Inc., a corporation of California

Filed Sept. 26, 1968, Ser. No. 13,723

Term of patent 14 years

Int. Cl. D23—01

U.S. Cl. D23—2

FIG. 1

FIG. 2

FIG. 3

FIG. 4

FIGURE 1 is a perspective view of the bulk material container embodying my new design;

FIGURE 2 is a top plan view thereof;

FIGURE 3 is a front elevational view thereof, the rear being the same as the front shown; and

FIGURE 4 is an elevational view taken from one side thereof, the opposite side being the same as the side shown.

I claim:

The ornamental design for a bulk material container, as shown and described.
